UNITED STATES PATENT OFFICE.

ARNO W. FOWLER, OF COLLINSVILLE, ILLINOIS.

CLOCK-WINDING MECHANISM.

Application filed August 16, 1926. Serial No. 129,364.

This invention relates to a clock winding mechanism, and comprises a winding device for winding the spring of the clock, an electric motor having a circuit including a switch controlled in a novel manner by the clock mechanism to close the circuit and operated by the motor in a winding operation to open the circuit at the proper time.

As shown in the accompanying drawings 10 the invention is embodied in a clock having a striking mechanism, controlling devices under control of the timing mechanism of the clock and equipped with an electric motor for winding purposes provided with 15 an electric circuit equipped with a switch, and a controlling device therefor whereby the switch is opened and closed properly.

An object of the invention is to provide a clock winding mechanism embodying the 20 construction and characterized by the mode of operation above stated, in general terms, and possessing the advantages apparent and inherent in the construction hereinafter more particularly described whether contained in a clock to indicate time only, or 25 in a clock equipped with striking mechanism and separate actuators for the time indicating mechanism and striking mechanism, wherein operation of the striking mechanism 30 is controlled by the running of the time indicating mechanism, and the motor for each actuator is controlled by the mechanism with which it is associated.

Other objects will appear from the following description, reference being made to the accompanying drawings, in which

Fig. 1 is a plan view of a clock work comprising time indicating and striking mechanisms and having my improved winding device operatively connected with it.

Fig. 2 is a front elevation with parts of the supporting frame plates broken away.

Fig. 3 is a vertical sectional view showing the connection of the motor with the 45 winding device and switch control.

Fig. 4 is an enlarged view showing parts of the switch opening device.

Fig. 5 is a detailed view showing a portion of the switch closing device.

Fig. 6 is a vertical cross sectional view 50 showing one of the clock actuating springs and the relationship to the switch actuators.

Fig. 7 is a detail sectional view of the switch in an intermediate position across 55 which the switch moves when being operated from closed to open position, and vice versa.

Fig. 8 is a view showing the relationship and direction of movement of the switch actuators.

The time indicating mechanism comprises a shaft 1 to which one end of an actuating spring 2 is attached, the opposite end of said spring being connected with a spring barrel 3 in which the spring is enclosed. The spring barrel 3 is attached to a large gear 60 wheel 4 loosely supported upon the shaft 1 and in mesh with a worm 5 rigid on the shaft 6 of an electric motor 7. When the motor is operated the shaft 6 and worm 5 and thereby gear wheel 4 are rotated in a 70 direction to wind the spring 2, which gradually unwinds as it operates the clock mechanism.

The two circuit wires for the motor are indicated by 8 and 9, respectively. Each 75 of the circuit wires is provided with a contact terminal 10 in the cavity of a hollow insulating switch block 11. The contact terminals 10 are in spaced relationship so that the gap between them must be bridged 80 to close the circuit. The switch shown more particularly in Figs. 7 and 8 is of known construction, comprising a circumferentially grooved roller 12 operative within the switch block 11 to and from position to 85 bridge the gap between the contact terminals 10 of the electric circuit wires as required to close and to open the circuit to the motor. The device for actuating the roller 12 to open and to close the circuit comprises a 90 lever 13 which, when moved to the position of the dotted line 14 (Fig. 7), causes the roller 12 to assume the position outlined by dotted lines at 15 closing the circuit; and, when the lever 13 is moved to the position 95 of the dotted line 16 it causes the roller to assume the position outlined by dotted lines at 17 opening the circuit. Since the switch is of known construction and mode of operation and it is known that the switch operates in this way, further detailed description thereof is not necessary.

The invention comprising the device for actuating the switch to close and to open the circuit may be readily understood by proceeding with the description on the assumption that the clock is running from a preceding winding. When the clock is running the shaft 1 is slowly turned by the spring 2 (Fig. 6). A pinion 18 attached to the shaft 1 meshes with and operates a pinion 19 rotative on a stud 20 and provided with and

connected to a hub or sleeve 21 to which a disc 22 is attached. The disc 22 supports a pair of laterally projecting pins 23. The disc 22 is attached to a hub 24 which, in 5 turn, is attached to and rotates with the sleeve 21. The hub 24 is provided with an end flange 25. An arm 26 is pivoted on the hub 24 between the flange 25 and the spacing washer 27, said washer holding the arm 26 10 spaced from the disc 22. The arm 26 extends between the two pins 23. When the clock is running the disc 22 and the arm 26 are operated in a clockwise direction, as indicated by the arrow 28 (Fig. 8). A spring 15 29 connects the arm 26 with the disc 22 and yieldingly holds said arm against the advance pin 23. When the switch is open the lever 13 is on the line 16 (Fig. 7) and in the position shown in Fig. 8, and is in the path 20 of movement of a pin 30 on the end of the arm 26. By the running of the clock the pin 30 is moved into contact with the outer side of the lever 13. The resistance to the operation of the lever 13 is greater than the 25 power of the spring 29, so that said spring yields and the switch is not operated until the rear pin 23 engages and moves the arm 26 a sufficient distance to move said lever 13 beyond the middle position shown in solid 30 lines (Fig. 7) toward closed position 14; whereupon, as is known, the switch automatically snaps to closed position 14—15. Thereupon the spring 29 acts to move the arm 26 quickly against the advance pin 23 where it 35 is held until a subsequent operation of the switch thereby.

Closing of the circuit by moving the lever 13 to closed position 14 and the roller 12 to position 15 (Fig. 7) causes the motor to operate, with the result that the wheel 4 is 40 turned in a counterclockwise direction, as indicated by the arrow 31 (Fig. 8) to wind the spring 2. The wheel 4 is on a hub 32 having an end flange 33. An arm 34 is pivoted on the hub 32 between the flange 33 and a spacing washer 35 which washer holds the arm 34 spaced from the wheel 4. The arm 34 has a pin 36 extending between the spokes of the wheel 4 and limiting extent of swinging movement of said arm with respect to the wheel 4. A spring 37 connects the arm 45 34 with the wheel 4 and yieldingly holds said arm in the position in which the pin 36 is against the adjacent spoke of the wheel 4, which is in advance during counterclockwise 50 turning movement of the wheel 4 in a winding operation. Winding turning movement of the wheel 4 ultimately engages a pin 38 on the arm 34 with the lever 13. The resistance to the operation of the lever 13 is 55 greater than the power of the spring 37, so that said spring yields and the switch is not operated until the pin 36 is in engagement with the rear one of the two spokes of the 60 wheel 4, between which said pin 36 extends,

and the pin 38 is thereby caused to move the lever 13 a sufficient distance on the middle position shown in solid lines (Fig. 7) toward open position 16; whereupon, as is known, the switch automatically snaps to open position 16—17. Thereupon, the spring 37 acts to move the arm 34 quickly to position in which the pin 36 is against the advance one of the two spokes of the wheel 4 between which said pin 36 extends, where it is held until a subsequent winding operation caused by operating the switch to closed position by the running of the clock, as previously described. 70 75

When the lever 13 is thus moved to open position 16, it is slightly to one side of the plane of the end of the pin 38 so that said lever 13 can be moved to closed position 14 by the arm 26 and pin 30 during running of the clock without being obstructed by the pin 38. This result is obtained by mounting the block 11 at such an angle of inclination that when the lever 13 is in the open position 16, it is in the path of movement of the pin 30 and out of the path of movement of the pin 38; and, when the lever 13 is in closed position 14, it is closer to the wheel 4 and in the path of movement of the pin 38 for operation thereby to open the circuit at or about the time winding of the spring 2 is completed. 80 85 90

The actuating shaft 1^a of the striking and chiming mechanism of the well known type of clock shown is arranged to be operated intermittently by a spring enclosed in a barrel 3^a, in all respects similar to the spring 2 which operates the shaft 1, so that it is unnecessary to illustrate in detail the spring 2 and its connection with the winding gear 4^a which is like the winding gear 4. 95 100

The mechanism comprising the parts 39 controls the operation of the shaft 1^a by its said spring, and the setting of the parts 39 for striking and chiming operations is, as is well known, controlled by the running of 105 the time indicating mechanism. The gearing of the time indicating mechanism for controlling the setting of the parts 39 is shown but requires no detail description, as the same is well known. For present purposes it is sufficient to assume that the striker and chiming devices are actuated as stated by the spring in the barrel 3^a, and that it is only necessary to rotate the wheel 4^a in the same manner that the wheel 4 is 110 rotated to wind the said spring in the barrel 3. 115 120

There is a separate motor 7^a having a worm 5^a on its shaft 6^a engaging the wheel 4^a, similar to the structure previously described. All of the devices controlling the opening and closing of the circuit to the motor 7^a are duplicates of the devices above described and the same reference numerals are applied to like parts including the letter 125 130

“a” added to the reference numerals of the striker winding mechanism. Thus, it will be understood that the lever 13^a is swung to position to close the circuit to the motor 7^a by the pin 30^a; that upon closing the circuit to the motor 7^a the motor operates to wind the spring in the barrel 3^a and to cause the pin 38^a ultimately, at or about the time the winding operation is completed, 10 to actuate the lever 13^a to open the circuit and stop the running of the motor. Thus the mechanism comprising the striking devices, the operation of which is controlled in the usual way by operation of the time 15 indicating mechanism, is equipped with an independent winding device.

From the foregoing it will be seen that my improved winding mechanism is of a highly efficient and satisfactory character, 20 and the operation thereof is automatically controlled and that it is necessary to provide only a comparatively few parts in addition to the usual clock mechanism. The cost of the clock including the present invention is not greatly increased over the cost of the clock without such mechanism, a considerable proportion of the additional cost being due to the motor or motors. The construction and arrangement of the parts 25 may be varied without departure from the nature and principle of the invention in which respects I do not restrict myself unessentially, but claim and desire to secure by Letters Patent:

30 1. I claim:

1. The combination with an actuating shaft and a spring for actuating said shaft, of a gear wheel on said shaft for winding said spring, an electric motor for rotating said gear wheel to wind said spring, a circuit for said motor, a switch for opening and closing said circuit, a support, a device pivoted on said support and operated by said spring in one direction for moving said 40 switch to closed position, and a device pivotally supported by said shaft and operated by said gear wheel in the opposite direction from said first device for moving said switch to open position.

50 2. The combination with an actuating shaft and a spring for actuating said shaft, of an electric motor, means operated by said motor for winding said spring, an electric circuit for said motor, a switch for opening and closing said circuit, a support, an element rotative on said support eccentrically of said shaft and actuated by said spring for closing said switch once during each complete rotation of said element, and 55 another rotative element pivoted concentrically with respect to said shaft and driven by said winding means to open said switch once during each complete rotation of said other element.

60 3. The combination with an actuating

shaft and a spring for rotating said shaft, of a gear wheel rotative on said shaft to wind said spring, an electric motor geared to said gear wheel for rotating the same in winding operations, an electric circuit for 70 said motor, a switch for opening and closing said circuit, a disc, gearing operated by said spring for rotating said disc, an arm pivotally supported concentrically with said disc, means for operating said arm by said disc 75 and permitting limited extent of movement of said arm relative to said disc, a part operated by said arm to close said switch, an arm pivotally supported concentrically with said gear wheel, and means operated by 80 said gear wheel for causing said second arm to open said switch.

4. The combination with an actuating shaft and a spring for rotating said shaft, of a gear wheel loose on said shaft and attached to said spring for winding said spring, an electric motor geared to said gear wheel for rotating said gear wheel in winding operations, an electric circuit for said motor, a switch for opening and closing said 90 circuit, a rotary arm driven by said spring for closing said switch once during each complete rotation of said arm, an arm pivotally supported adjacent to said gear wheel, and means for operating said second arm by 95 said gear wheel and causing said second arm to open said switch at the completion of a rotation of said second arm by said gear wheel.

5. The combination with an actuating shaft and a spring for rotating said shaft, of a gear wheel loose on said shaft and attached to said spring for winding said spring, an electric motor geared to said gear wheel for operating said gear wheel in winding operations and preventing turning of said gear wheel by said spring, an electric circuit for 100 said motor, a switch for opening and closing said circuit, means driven by said spring for closing said switch, an arm pivotally supported adjacent to said gear wheel for movement relative to said gear wheel, means for operating said arm by said gear wheel and causing said arm to open said switch at the completion of a winding operation of said gear wheel by said motor, and a spring connecting said arm with said gear wheel and permitting movement of said arm relative to said gear wheel.

105 6. The combination with an actuating shaft and a spring for rotating said shaft, of a gear wheel loose on said shaft and attached to said spring for winding said spring, an electric motor geared to said gear wheel for operating said gear wheel in winding operations and preventing turning of said gear wheel by said spring, an electric circuit for 110 said motor, a switch element for opening and closing said circuit, a lever for moving said switch element, a support, an arm pivoted

115 to said support, an element rotative on said support eccentrically of said shaft and actuated by said spring for closing said switch element once during each complete rotation of said element, and another rotative element pivoted concentrically with respect to said shaft and driven by said winding means to open said switch element once during each complete rotation of said other element.

120 7. The combination with an actuating shaft and a spring for rotating said shaft, of a gear wheel loose on said shaft and attached to said spring for winding said spring, an electric motor geared to said gear wheel for operating said gear wheel in winding operations and preventing turning of said gear wheel by said spring, an electric circuit for 125 said motor, a switch element for opening and closing said circuit, a lever for moving said switch element, a support, an arm pivoted

- on said support, means for rotating said support by said spring, means on said support for actuating said arm in one direction and causing said arm to move said lever to close 5 the switch, and an arm operatively connected with and moved by said gear wheel in the opposite direction from the movement of said first named arm for actuating said lever to open the switch.
- 10 7. The combination with an actuating shaft and a spring for actuating said shaft, of a gear wheel on said shaft for winding said spring, an electric motor for rotating said gear wheel to wind said spring, a circuit 15 for said motor, a switch for opening and closing said circuit, an element supported eccentrically of and rotated by said shaft, an arm pivoted concentrically and adjacent to said element, means for rotating said arm by said element and permitting limited extent of movement of said arm relative to said element, and means for actuating said switch by said arm to close said circuit.
- 20 8. The combination with an actuating shaft and a spring for actuating said shaft, of a gear wheel on said shaft for winding said spring, an electric motor for rotating said gear wheel to wind said spring, a circuit 25 for said motor, a switch for opening and closing said circuit, an element supported eccentrically of and concentrically rotated by said shaft, an arm pivoted concentrically and adjacent to said element, abutments on said element limiting extent of and permitting independent 30 movement of said arm relative to said element, a spring connecting said arm and said element, a lateral extension on said arm arranged to engage and operate said switch to closed position, an arm pivoted adjacent to said gear wheel, means for rotating said arm by said gear wheel, and means for operating said switch by said second arm to open said circuit.
- 35 9. The combination with an actuating shaft and a spring for actuating said shaft, of a gear wheel on said shaft for winding said spring, an electric motor for rotating said gear wheel to wind said spring, a circuit 40 for said motor, a switch for opening and closing said circuit, an element supported eccentrically of and rotated by said shaft, an arm pivoted concentrically and adjacent to said element, means for rotating said arm by said element and permitting limited extent of movement of said arm relative to said element, means for actuating said switch by said arm to close said circuit, an arm pivoted concentrically with and adjacent to said gear wheel, means for rotating said arm by said gear wheel, and means for operating said switch by said second arm to open said circuit.
- 45 10. The combination with an actuating shaft and a spring for actuating said shaft, of a gear wheel on said shaft for winding said spring, an electric motor for rotating said gear wheel to wind said spring, a circuit 50 for said motor, a switch for opening and closing said circuit, an element rotated by said shaft, an arm pivoted adjacent to said element, abutments on said element limiting extent of and permitting independent movement of said arm relative to said element, a spring connecting said arm and said element, a lateral extension on said arm arranged to engage and operate said switch to closed position, an arm pivoted adjacent to said gear wheel, means for rotating said arm by said gear wheel, and means for operating said switch by said second arm to open said circuit.

ARNO W. FOWLER.
